UNITED STATES PATENT OFFICE

132,373

DESIGN FOR A COMBINED CONVEYER AND MIXER FOR STOCK FEEDS, FLOURS, AND THE LIKE

Vance J. Coleman, Cedar Rapids, Iowa

Application September 12, 1941, Serial No. 103,315

Term of patent 7 years

To all whom it may concern:

Be it known that I, Vance J. Coleman, a citizen of the United States, residing at Cedar Rapids, in the county of Linn and State of Iowa, has invented a new, original, and ornamental Design for a Combined Conveyer and Mixer for Stock Feeds, Flours, and the like, of which the following is a specification, reference being had to the accompanying drawings, forming part thereof.

Figure 1 is a view in perspective of one end and

side of a combined conveyer and mixer for stock feeds, flours, and the like, embodying my new design and,

Figure 2 is a view in perspective of the other end and side thereof.

I claim:

The ornamental design for a combined conveyer and mixer for stock feeds, flours, and the like, as shown.

VANCE J. COLEMAN.
